PORTABLE WARNING UNIT

Samuel Reuben, Jr., 515 Jackson Ave., Glencoe, Ill.

Filed Mar. 25, 1959, Ser. No. 55,168

Term of patent 14 years

(Cl. D72—1)

Fig. 1 is a front perspective view of a portable warning unit showing my new design in the open position with the electric cord shown broken away in part to indicate indeterminate length; and

Fig. 2 is a top plan view of Figure 1.

The exterior surfaces of the rear, bottom and left side, which surfaces are not shown, are substantially plain. The exterior surface of the top side, which surface is not shown, is similar to the interior surface of the top side as shown. The dominant features of my design reside in the full line portions of the drawing.

I claim:

The ornamental design for a portable warning unit, substantially as shown and described.
